PACKER

Original Filed Jan. 22, 1925

UNITED STATES PATENT OFFICE

HARVEY R. STANDLEE, OF TULSA, OKLAHOMA, ASSIGNOR TO THE GUIBERSON CORPORATION, OF DALLAS, TEXAS, A CORPORATION OF DELAWARE

PACKER

Application filed January 22, 1925, Serial No. 3,960. Renewed April 24, 1929.

The present invention is designed as an improvement over that form of packer shown in my prior application, Serial Number 746,486, filed October 29, 1924, in which 5 the specific cooperation between the packer and the setting means is specifically set forth and claimed.

The conservation of gas pressure by the early application of a packer in a well is recognized by those skilled in the art as such a 10 step permits a continued natural flow for an indefinite period thereby eliminating the expense and labor involved in the use of tubing and pumping apparatus.

15 The present construction is designed to facilitate application within a casing under any condition regardless of gas pressure or nature of the well as to paraffin percentage, and without injury to the destructible 20 elements involved in the packer assembly or to the well itself. In addition the same advantageous jarring effect between the tubing collar and the dog guide block is present.

25 The foregoing is accomplished by the novel combination and arrangement herein shown and described which includes the provision of the springs on the straps between the dogs and the collar; the inverted U-shaped slot and co-operating pin for controlling setting of the packer and the provision of the backing collars for the rubber packer element to cause the latter to normally expand outwardly.

35 Numerous other advantages and features of construction will hereinafter appear by reference to the following specification and claims and attached drawings forming a part of this application and wherein like numerals of reference designate corresponding parts throughout the several views in which:

Fig. 1 is a side elevation,

Fig. 2 is a side vertical sectional view,

45 Fig. 3 is a section on line 3—3 of Fig. 2, and

Fig. 4 is a section on line 4—4 of Fig. 2.

The main elements of the present arrangement are in general similar to the corresponding elements of my prior application 50 heretofore mentioned. For the purpose of

illustration a well casing 1 is shown in section and the tubing carrying the packer is indicated by reference character 2. The expandable packer element includes the rubber tubing 3 fixed to the upper and lower collars 4. These collars 4 each are formed with annular projections 5 which extend well within the rubber packer 3 to permit the engagement of their adjacent ends when the packer is set. This arrangement not only prevents the collapsing of the packer inwardly under gas pressure but also assists in supporting the tubing which otherwise would rest entirely on the rubber. This is quite important and considerably extends 55 the life of the packer. The necessary ports 6 formed in the inner walls of the collars 4 to permit the escape of the gas when desired are regulated and controlled by the valve 7 fixed to the tubing 2 and this valve is normally unseated due to the pressure of the spring 8, between the valve and the upper collar, see Figure 1.

Immediately below the packer is the slip on dog guide block 9 of frusto conical formation and as in the instance of the packer arranged to slide with relation to the tubing. This block 9 is internally grooved for the passage of fluid. The external shape of the block is optional and may be triangular, square or otherwise in cross-section, as necessity may demand and according to the number and arrangement of the gripping members on dogs 10 desired.

The flattened faces of the block 9 are 75 formed with central longitudinal dovetail grooves for the reception and travel of the male dovetail carried by each dog. Cooperative action by the several dogs 10 is obtained by the use of the collar 11^a which is connected to the dogs by means of straps 12 and is adapted for longitudinal movement on the tubing. These straps 12 are spaced by means of suitable slots 14 formed 80 in the lower flange 15 of the block 9. Coil springs 16 are arranged on each strap between the block and the flange 14 and exert a normal pressure upwardly to seat the dogs. 85 To cause the engagement of the dogs 10 90

with the inner face of the casing 1 there is provided the sleeve 11 adapted as in the instance of the collar 11^a for longitudinal movement on the tubing. This sleeve 11 is provided with a slot of inverted U design which acts as a guide for the pin 17 fixed to and extending from the filler block or tube 18 arranged between the collar and the tubing. This filler 18 carrying the pin is fixed in position to the tubing by means of the adjacent couplings of the tubing between which it is arranged. The function of the slot and pin will be obvious when considering the movement of the elements in running and seating the packer, as will also the provision of the elongated portion of the slot. Leaf springs 19 are mounted on sleeve 11 to act as drags therefor and normally engage the inner face of the casing.

In operating this combined packer and tubing catcher it will be seen that while the tubing 2 is being lowered into the well the pin 17, fixed on the tubing, will press on the lower end of the short leg of the slot 21, and pull the sliding sleeve 11 downwardly with the tubing. During this movement, the friction springs 19 will bear against the casing and cause the sleeve 11 to drag so that it will not drop down on the tubing. As the tubing descends the collar 11^a will occupy the position shown in Figure 1, it being heavy enough to compress the springs 16 while the lower end of the guide block 9 is resting on the coupling 2^a. While the coupling 2^a is supporting the guide block, the collar 4 is resting on the upper end of the guide block and the spring 8 is forcing the upper collar 4 downwardly as shown in Figure 1.

When the tubing has been lowered to a point where the packing is to be anchored, the operator lifts the tubing 2 sufficiently to cause the pin 17 to rise to the top of the slot 21, and then the tubing is turned to drop the pin 17 in the long leg of the slot. Then as the tubing descends, the collar 11^a will be prevented from descending by the sleeve 11 and consequently the dogs 10 remain stationary while the guide block 9 is being forced downwardly by the packer under the influence of the valve 7 which is fixed on the tubing. At this time the guide block will be locked to the casing, the packer will be expanded somewhat due to the pressure upon its opposite ends, and the packer will be expanded further owing to the fact that the fluid in the well can enter the packing. Obviously a reversal of this operation will put the parts in position to be withdrawn from the well.

Particular attention is called to the large amount of clearance which provides for running in oil of heavy gravity from a paraffine base. This clearance permits movement of all parts under these and all other circumstances.

When the present device is seated the gas pressure enters the grooves in the block 9 and the grooves in the collar 5 to expand the rubber packer 3 to pack off the well. When it is desired to remove the packer from the well the tubing is picked up thus raising the valve 7 from its seat and allowing the gas pressure to escape. Upon this reduction of gas pressure the rubber packer 3 returns to its normal position without damage to itself.

A continued upward movement will cause the pin to travel to the upper extremity of the longer leg of the slot and during this movement the coupling 2^a will lift the block 9 to release the slips 10. As the block 9 rises, the fingers 14 will compress the springs 16 and finally lift the slips. The slips will then lift the collar 11^a out of engagement with the sleeve 11. Should a binding occur between the dogs 10 and the casing a jarring can be obtained by upward movement of the collar 2^a against the block 9.

It will thus be seen that the tubing 2 has been provided with an element 7 and an element 18 each fixed thereon, between which is arranged a packer and setting means for the packer, said setting means forming the lower stop for the packer, when the packer is not expanded, permitting removal of said packer from the well. All of the elements set forth obviously cooperate with each other to the desired result of accurately setting a packer and preventing wear and tear thereon when in use.

What I claim as new and useful and desire to secure by Letters Patent is:

1. In a packer for oil wells, a casing therefor, tubing within said casing, an expandable packer arranged for longitudinal movement on said tubing and having internal ports therethrough, a valve fixed to said tubing for closing said ports, means for normally holding said valve from its seat, a guide block arranged on said tubing immediately below said packer and formed with tapering flat surfaces, dogs mounted thereon, a collar on said tubing below said guide block, straps connecting said dogs to said collar, a sliding sleeve, and leaf springs fixed to said sliding sleeve and in engagement with said casing.

2. In a packer for oil wells, a casing therefor, tubing within said casing, an expandable packer arranged for longitudinal movement on said tubing and having internal ports therethrough, a valve fixed to said tubing for closing said ports, means for normally holding said valve from its seat, a guide block arranged on said tubing immediately below said packer and formed with tapering flat surfaces, dogs mounted thereon, a collar on said tubing below said guide block, straps connecting said collar to said dogs, and a spring for each dog normally forcing the same into engagement with said casing.

3. In a packer for oil wells, a casing therefor, tubing within said casing, an expansible packer arranged for longitudinal movement on said tubing and having internal ports therethrough, a valve fixed to said tubing for closing said ports, means for normally holding said valve from its seat, a guide block arranged on said tubing immediately below said packer formed with tapering flat surfaces, dogs mounted thereon, a collar on said tubing below said guide block, a sliding sleeve, a vertical guideway formed in said sliding sleeve, a filler sleeve between said collar and said tubing formed with a pin for normal engagement in said guideway, said filler sleeve being fixed with relation to said tubing, straps connecting said dogs to said collar, and springs carried by said sliding sleeve normally engaging said casing. 70
- 10 4. In a device of the class described including a casing and a tubing arranged therein, a guide block arranged for limited movement on said tubing and formed with a plurality of spaced flat tapering faces, grooves of dovetailed cross section extending longitudinally at intermediate points in each flat surface, blocks formed with dovetails arranged to travel in said grooves and having outer gripping surfaces for engagement with said casing, means controlled by the movement of the tubing for moving said blocks longitudinally, and a packer arranged on said tubing having a longitudinal passage and a valve controlled by the movement of the gripping blocks. 80
- 20 5. In a device of the class described including a casing and a tubing arranged therein, a guide block arranged for limited movement on said tubing formed with a plurality of spaced flat tapering faces, grooves of dovetailed cross section extending longitudinally at intermediate points in each flat surface, blocks formed with dovetails arranged to travel in said grooves and having outer gripping surfaces for engagement with said casing, means controlled by the movement of the tubing for moving said blocks longitudinally, an expansible packer arranged on said tubing having a longitudinal port and a valve for said port controlled by the longitudinal movement of said tubing. 90
- 30 6. In a device of the class described including in combination, a casing, a tubing, a packer arranged on said tubing, a guide block slidably arranged on said tubing adjacent said packer, dogs adapted to travel on said guide block and engage said casing, straps connected to said dogs, a sliding collar on said tubing, said straps being connected to said collar, springs on said straps normally tending to cause the engagement of said dogs with said casing, a sliding sleeve on said tubing below said collar formed with an inverted U-shaped slot one leg of which being substantially twice the length as the 100
- 40 other leg, a filler tube between said sliding sleeve and tubing and fixed to the tubing, a pin carried by said filler tube engaging and being adapted to travel in said slot, and a series of flat springs fixed to said sliding sleeve and normally engaging said casing. 110
- 50 7. In a packer for oil wells, a casing for said oil well, tubing within said casing, an expansible packer arranged for longitudinal movement on said tubing and having internal ports therethrough, a valve fixed to said tubing for closing said ports, means for normally holding said valve from its seat, a guide block arranged on said tubing immediately below said packer, dogs mounted thereon, a collar on said tubing below said guide block, a sliding sleeve, a guideway of substantially inverted U design formed in said sliding sleeve, a member fixed to said tubing within said sliding sleeve and formed with a fixed pin for engagement and travel within said guideway, straps connecting each dog to said collar, and friction means carried by said sliding sleeve for engagement with the inner wall of said casing to fix the sliding sleeve in position in the casing. 120
- 60 8. A packer for oil wells including in combination with casing and tubing, a rubber tubular section mounted on said tubing, collars for each end of said rubber tubing formed with annular grooves for the reception of the extremities of the same, each of the inner walls of said collars forming said grooves extending inwardly a substantial distance beyond the outer wall to permit their engagement upon seating of said packer and to form reinforcement for said rubber section, said inner walls being grooved for the passage of fluid, and a valve fixed to the tubing for closing said fluid passages. 130
- 70 9. A packer for oil wells including in combination with casing and tubing, a rubber tubular section mounted on said tubing, collars for each end of said rubber tubing formed with annular grooves for the reception of the extremities of the same, each of the inner walls of said collars forming said grooves extending inwardly a substantial distance beyond the outer wall to permit their engagement upon seating of said packer and to form reinforcement for said rubber section, said inner walls being grooved for the passage of fluid, a guide block immediately below said packer element arranged for movement on said tubing and formed with guide surfaces, dogs engaging said guide surfaces and adapted for engagement with said casing, and means for forcing said dogs upwardly into engagement with said casing during the lowering of the packer. 140
- 80 10. A packer for oil wells including in combination with casing and tubing, a rubber tubular section mounted on said tubing, collars for each end of said rubber tubing 150

formed with annular grooves for the reception of the extremities of the same, each of the inner walls of said collars forming said grooves extending inwardly a substantial distance beyond the outer wall to permit their engagement upon seating of said packer and to form reinforcement for said rubber section, said inner walls being grooved for the passage of fluid, a guide block immediately below said packer element arranged for movement on said tubing and formed with guiding surfaces, dogs engaging said guiding surfaces and adapted for engagement with said casing, means for moving said dogs upwardly into engagement with said casing, comprising a sleeve section formed with a guideway, a member between said sleeve section and said tubing having a pin for travel within said guideway, and means for frictionally engaging said sleeve section with said casing.

11. In a device of the class described, in combination with casing and tubing for an oil well, an expansible packer arranged on said tubing for longitudinal movement and formed with internal longitudinal ports, a valve for said ports fixed to said tubing, a spring for normally spacing said valve and valve seat, a guide block arranged on said tubing immediately below said packer and being adapted for longitudinal movement, said guide block being formed with inclined faces having guiding surfaces, a plurality of dogs slidably engaging said guide surfaces, and means for moving said dogs as a unit including a plurality of straps connected to said dogs, guide slots at the lower end of said block for preventing lateral movement of said straps, springs arranged on said straps between said dogs and said guide slots, a collar to which the lower extremities of said straps are connected, and a sliding sleeve engaging said collar.

12. In a device of the class described, in combination with casing and tubing for oil wells, an expansible packer arranged on said tubing for longitudinal movement and formed with internal longitudinal ports, a valve for said ports fixed to said tubing, a spring for normally spacing said valve and valve seat, a guide block arranged on said tubing immediately below said packer and being adapted for longitudinal movement, said guide block being formed with a plurality of flat inclined faces each having intermediate grooves, a plurality of dogs formed with extensions for engagement in said grooves, means for moving said dogs as a unit including a plurality of straps connected to said dogs, guide slots at the lower end of said block for preventing lateral movement of said straps, springs arranged on said straps between said dogs and said guide slots, a collar to which the extremities of said straps are connected, a sliding sleeve for controlling said collar, means for limiting the vertical move-

ment of said sliding sleeve, and friction means on said sleeve to engage the casing and fix the sleeve in said casing.

13. In a device of the class described, in combination with casing and tubing for oil wells, an expansible packer arranged on said tubing for longitudinal movement and formed with internal longitudinal ports, a valve for said ports fixed to said tubing, means for normally spacing said valve and valve seat, a guide block arranged on said tubing below said packer and being adapted for longitudinal movement, a plurality of dogs movably mounted on said guide block, dog actuating means for moving said dogs as a unit to cause them to grip the casing, a sliding sleeve engageable with the dog actuating means to prevent said dog actuating means from descending with the tubing at a certain time so as to cause the dogs to grip the casing, said sliding sleeve having a guideway including substantially vertical legs connected by a cross-head, one leg being longer than the other, and a pin fixed to the tubing and slidably engaging said guideway.

14. In a device of the class described, a casing, an inextensible tubing arranged therein and adapted to extend to the top of the well for conveying fluid to the top of the latter, an expansible packing structure on the tubing consisting of upper and lower metal rings and an intermediate resilient sleeve, means on the tubing for pressing the packing structure downwardly, a guide block arranged for limited movement on the tubing below the packing structure, the packing structure resting on said guide block, a ring arranged on the tubing and adapted to move axially of the latter, links connected to said ring, dogs connected to said links and movable by the guide block for gripping the casing, and means controlled by the movement of the tubing independently of said ring for moving the dogs into engagement with the casing.

15. In a device of the class described including a well casing and a tubing arranged therein, a stop fixed to the tubing, a member mounted on the tubing, and having a guideway slidably engaging said stop, said guideway being of substantially inverted U-shape with one leg of the U longer than the other, said tubing being movable lengthwise and turnable relatively to said member and this relative movement being limited by the stop and guideway, friction means on said member engaging the casing and adapted to cause said member to drag during the lowering of the tubing and to fix said member in position temporarily while the tubing is being raised slightly, turned and then lowered to move the stop from the lower end of the short leg to the lower end of the long leg of the guideway, a collar slidably mounted on the tubing and adapted

to be engaged by said member to be prevented from lowering with the tubing while the stop is traveling down the lower portion of the long leg of the guide, a guide block 5 slidable on the tubing, dogs movably mounted on the guide block, straps connecting the dogs and collar for causing the dogs to grip the casing while the stop is traveling down the lower portion of the long leg of the 10 guideway, and the block is lowering with the tubing, a tubular expansible packing cooperating with the block and having a passage therethrough to permit fluid to travel through the same, and a valve on the tubing adapted to close said passage when the 15 packing is seated.

16. In a packer for wells, a casing therefore, tubing within said casing, an expansible packer arranged for longitudinal movement 20 upon said tubing and having an internal port therethrough, a valve fixed to the tubing for closing said port, means for normally holding said valve from its seat, guiding means arranged upon the tubing below said packer and formed with wedging surfaces, dogs 25 movably mounted upon said surfaces, an operating device surrounding said tubing below said guiding means and connected to said dogs, a sliding member upon the tubing, and friction devices acting upon said 30 sliding member and engaging the casing.

17. In a packer for wells, a casing therefore, a tubing within said casing, an expansible packer arranged for longitudinal movement 35 upon said tubing and having an internal port therethrough, a valve fixed to the tubing for closing said port, guiding means arranged upon the tubing below said packer movably independently thereof and formed with wedging surfaces, dogs 40 movably mounted upon said surfaces, a sliding member upon the tubing arranged to support said dogs, tension members disposed between the dogs and guiding means, and friction 45 devices acting upon said sliding member and engaging the casing.

18. In a packer for wells, a casing therefore, a tubing within said casing, an expansible packer arranged for longitudinal movement 50 upon said tubing and having an internal port therethrough, a valve fixed upon the tubing for closing said port, a guide block mounted to slide upon the tubing independent of the packer and formed with 55 wedging surfaces, dogs movably mounted upon said surfaces, a sliding member upon the tubing arranged to support said dogs, and friction devices movable upon the tube 60 independently of said sliding member and engaging the casing.

19. In a device of the class described, in combination with a casing and tubing for wells, an expansible packer arranged on said tubing for longitudinal movement and 65 formed with a longitudinal port, a valve for

said port fixed to said tubing, a longitudinally movable guide block arranged upon the tubing below and independently of said packer, movable gripping means upon said guide block, yielding supporting means between the block and gripping means, a sliding sleeve upon the tubing having connections engageable with the gripping means, said sleeve having a guideway including substantially parallel vertical legs of different 70 lengths connected by a cross head, and a pin fixed to the tubing and slidably engaging said guide way.

20. A packer for wells comprising an expansible tubular section of yielding material, and collars having annular seats embracing the opposite ends of said section and formed with free extensions disposed within the section and spaced to permit their axial travel into engagement upon the seating of the packer.

21. A packer for wells, a tubing, a friction member movably connected to the tubing to engage a casing, casing gripping members adapted to be supported by the friction member, a guide block movable upon the tubing to engage the gripping members with the casing, a yielding support interposed between said members and guide block, a packer movable upon the tubing independently of said guide block, and means fixed upon the tubing to impart longitudinal movement to the packer and guide block.

22. In a device of the class described, a tubing, an expansible packer mounted on the tubing, a guide block slidable upon the tubing independently of the packer and having inclined faces, dogs slidable mounted on the block faces for engaging a casing, springs interposed between said dogs and block, a yieldable support for said dogs free to slide on said tubing, and anchoring means for engaging a casing and also for engaging said support for setting said dogs to expand said packer when the tubing is lowered.

23. In a device of the character described, a tubing, an expansible packer mounted thereon, a guide block axially movable upon the tubing and having inclined faces, means upon the tubing for moving said block in one direction, dogs disposed to engage a casing by a sliding movement on said faces in said movement of the block, supporting springs disposed between the dogs and block, and anchoring means disposed to engage said casing and support the dogs.

In testimony whereof I affix my signature.
HARVEY R. STANDLEE.
